UNITED STATES PATENT OFFICE.

WILLIAM J. REGAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING-LOCKING MECHANISM.

1,222,992.

Specification of Letters Patent. Patented Apr. 17, 1917.

Application filed December 12, 1916. Serial No. 136,494.

To all whom it may concern:

Be it known that I, WILLIAM J. REGAN, a citizen of the United States, residing at Pittsburgh, in the county of Allegheny and

5 State of Pennsylvania, have invented certain new and useful Improvements in Car-Coupling-Locking Mechanism; and I do hereby declare the following to be a full, clear, and exact description of the invention, 10 such as will enable others skilled in the art to which it appertains to make and use the same.

My invention relates to improvements in car couplers, and is especially directed to 15 the provision of means for preventing an unlocking movement of the coupler lock and the release of the knuckle when the coupler assumes an abnormal position as occurs when the car is bodily tilted or turned 20 over to discharge its contents.

Generally stated, my invention embraces the combination with a coupler head, a knuckle, and a lock therefor which projects through the coupler-head, of a latch member 25 pivotally mounted on the lock and normally maintaining a relation at right angles thereto, whereby when the coupler head is in an abnormal position tending to cause an unlocking movement of said lock said latch 30 may engage the outer face of the coupler head and prevent the unlocking movement of the coupler lock.

In the drawings chosen for the purpose of illustrating my invention, the scope whereof 35 is pointed out in the claims,

Figure 1 is a side elevation of a coupler embodying my invention, part of the coupler stem being omitted.

Fig. 2 is a plan view of the coupler shown 40 in Fig. 1.

Fig. 3 is a detail perspective view of the lower or projecting end of the lock member of the coupler, showing one form of latch member pivotally mounted thereon.

45 Fig. 4 is a front elevation of the coupler, turned upside-down, showing the position assumed by the latch member when operating to prevent the release of the coupler lock and knuckle.

50 Fig. 5 is a detail perspective view of a modified form of the projecting end of the lock and latch member pivotally mounted thereon.

Like symbols refer to like parts wherever 55 they occur.

In the drawings, 1 indicates a coupler head, which may be of the usual vertical plane or Master Car Builders' type and provided with a pivoted knuckle 2 which is engaged by a locking device 3 that serves to restrain the outward or uncoupling movement of the knuckle when in coupled relation with a coacting coupler.

In the present instance the lock 3 is illustrated as a vertically movable pin passing 65 through suitable openings in the top and bottom walls of the coupler head, and as having a clevis 4 for connecting it with the usual or any desired form of release rigging.

The lower end of the lock 3, as at 3^a, is 70 preferably of less cross-sectional area than that portion of the lock member which engages the tail piece of the knuckle 2, projects somewhat below the bottom wall of the coupler-head 1 and carries a latch member 75 5 pivotally mounted thereon.

The latch member 5 is of such length on either side of its pivot that either arm thereof will substantially correspond in length to the distance which the lock member 3 projects below the bottom wall of the coupler head 1 when the lock is in its lowest or locked position. This latch 5, which is preferably in the form of a flanged bar or channel, as indicated in Fig. 1 of the drawings, 80 is preferably connected to the lock member 3 by a cotter pin 6 which passes through perforations in the flanges of the channel bar and through the lower end of the lock member exteriorly of the coupler-head. The 85 latch is so balanced with relation to the locking member as to maintain a substantially horizontal position. It is thus normally so positioned beneath the bottom wall of the coupler head as to permit the usual 90 movements of the lock 3 to be effected by the release rigging so long as the coupler-head maintains its normal position.

If preferred, the latch member may be formed as a flat bar 7, of suitable width and 100 length, pivoted in an open slot 8 in the lower end of the lock member 3, as indicated in Fig. 5 of the drawing.

The operation of the latch member 5 (or 7) and its coaction with the coupler head 105 and lock, will be as follows:

As long as the coupler-head 1 maintains its normal position, the latch member (5 or 7) will maintain its normal or horizontal position beneath and substantially parallel 110

2
with the bottom wall of the coupler head and will not obstruct the unlocking movement of the lock 3. The latch (5 or 7) will continue to maintain its horizontal position 5 until the coupler-head 1 has rotated through an arc of ninety degrees or thereabout, whereupon one of the ends of the latch, depending upon the direction of rotation of the coupler, will engage the coupler head 10 and the latch will thereafter rotate with the coupler. While the end of the latch thus remains in engagement with the coupler head an unlocking movement of the lock 3 is prevented, as will be very readily perceived 15 upon reference to Fig. 4 of the drawings. When the coupler-head has returned to its normal position, the latch member (5 or 7) will resume its normal or horizontal position parallel with and beneath the coupler- 20 head.

I claim:

1. The combination with a coupler-head and a knuckle, of a lock member which projects outside the coupler-head, and a latch 25 device pivotally mounted on the projecting end of the lock member, the arms of said pivoted latch member being each of a length substantially equal to the distance of its pivotal point from the proximate wall of the 30 coupler-head.

2. The combination with a coupler-head

and a knuckle, of a lock member which projects below the bottom wall of the coupler head, and a latch member pivotally mounted 35 on the projecting end of the lock member and spaced with relation to the bottom wall of the coupler head when the lock member is in locked position.

3. The combination with a coupler-head, 40 a knuckle, and a vertically movable lock member which projects below the bottom wall of the coupler head, of a flanged latch member having a pivotal connection with the lock-member, the arms of said pivoted latch member on opposite sides of the pivot 45 being substantially equal in length and substantially equal to the distance the said pivotal point is below the bottom wall of the coupler head.

4. The combination with a coupler-head, 50 a knuckle, and a lock member, of a latch device normally spaced from said head but adapted to engage the same to prevent said lock member from moving to unlocked position, said latch device being movably connected to and normally projecting beyond said lock member and being movable into engagement with the coupler-head by the rotation of said head.

In testimony whereof I affix my signature. 60

WILLIAM J. REGAN.
